UNITED STATES PATENT OFFICE.

JOSEPH BAILEY, OF NEWARK, NEW JERSEY, ASSIGNOR OF ONE-HALF TO HENRY A. JAEGER, OF JERSEY CITY, NEW JERSEY.

MECHANICAL BATTLE.

1,214,744.

Specification of Letters Patent.

Patented Feb. 6, 1917.

Application filed October 19, 1916. Serial No. 126,557.

To all whom it may concern:

Be it known that I, JOSEPH BAILEY, a citizen of the United States, and a resident of Newark, in the county of Essex and State 5 of New Jersey, have invented a certain new and useful Improvement in Mechanical Battles, of which the following is a full, clear, and exact specification.

This invention relates to a class of amusement apparatus.

My invention has for its object primarily to provide a mechanically operative apparatus whereby a naval battle especially may be reproduced in miniature for display on 15 the stage of a theater and elsewhere, and which represents in an unusually interesting fashion a bombardment of objects on land as well as a battle between opposing fleets of war ships.

The invention consists essentially of one series, or a plural series of tracks, and movable on each track is a war vessel, the guns of a number of which being provided with lamps whereby firing of the guns may be 25 represented, while in each of the other vessels may be a magazine for holding a quantity of combustible material to produce a red flame of light. In each of the magazines in contact with the combustible material is a spark plug for igniting the 30 material, and in each vessel is a normally open electric circuit leading to each lamp and to each spark plug for lighting the lamps as well as energizing the spark plugs 35 at intervals, while in each circuit is one or more switches to permit the circuit to be closed and opened.

Other objects of the invention are to provide at spaced intervals on each track a 40 trip to operate the switch or switches of each vessel to close the circuit thereof when the vessel is moving; to provide objects as being on land for bombardment; to provide one or more lamps in each object; to 45 provide a normally open electric circuit leading from one or more of the tracks to the lamps of each object; to provide on one or a number of the vessels a switch for closing the circuit leading to the objects at intervals; and to provide at intervals on one 50 or more of the tracks movable trips for causing the electric circuit of one or more of the vessels to be closed in quick succession

for successively lighting the lamps during the movement of the vessels.

With these and other objects in view, the invention will be hereinafter more particularly described with reference to the accompanying drawings, forming a part of this specification in which similar characters of reference indicate corresponding parts in all the views, and will then be pointed out in the claims at the end of the description.

In the drawings, Figure 1 is a top plan of one form of mechanical battle embodying 65 my invention. Fig. 2 is a fragmentary view, partly broken away, showing a side elevation of one of the vessels used in the device as well as part of an electric circuit thereof. Fig. 3 is an enlarged fragmentary view 70 showing a top plan of part of one of the tracks of the apparatus. Fig. 4 is a fragmentary sectional view, partly in detail, taken on the line IV—IV of Fig. 2. Fig. 5 is an enlarged fragmentary view of part 75 of the track shown in Fig. 3. Fig. 6 is a side elevation, partly broken away, of another form of a vessel employed in the apparatus. Fig. 7 is an elevation of a building serving as one of the land objects used 80 in the apparatus. Fig. 8 is a perspective view of one of the switches used for closing the circuit in each of the vessels. Fig. 9 is a diagrammatic view of one of the electric circuits employed in the apparatus. Fig. 85 10 is a diagrammatic view of another electric circuit, and Fig. 11 is a diagrammatic view of still another electric circuit used in the apparatus.

The amusement apparatus, or mechanical 90 battle may be arranged on a board, or support, as 10, of any desired shape and size, and part of the top surface of this support may be painted or otherwise designed to represent land, as 11, while the other portion of the top surface of the support may be painted or designed to represent a water surface, as 12. On the water surface 12 of the support may be one, or a plural series of tracks, as 13 and 14, each series being 100 composed of a suitable number of spaced parallel tracks, for example four in number, as 15, 15^a, 15^b, 15^c and 16, 16^a, 16^b, 16^c, and the tracks of each series may be relatively disposed in any desired manner. All 105 of the tracks are preferably of similar for-

inations, and each track may be formed of a pair of spaced corresponding channel, or substantially U-shaped members to provide two spaced base-plates 19, 20, two spaced 5 upwardly extending inner flanges 21, 22, and two upwardly projecting outer flanges 23 and 24, the members of each track being connected by a number of cross-rods 25 provided at intervals between the inner flanges 10 of the track.

The pair of inner flanges of each track is of less height than the outer flanges, and movable on the upper edges of the inner flanges of each track of each series is a vessel 15 preferably of a form representing a battle ship so that the battle ships on one series of tracks will represent a fleet, while the battle ships on the other series of tracks will represent an opposing fleet. A number 20 of the battle ships, as 27, Fig. 2, are provided with guns, as 28, such as one in the fore and one in the aft of the ship, and one or more of the battle ships, as 29, Fig. 6, are provided with a magazine, as 30, for 25 holding a quantity of combustible material of any desired composition adapted to produce a flame of fire when ignited. Each of the battle ships 27 and 29 has a hollow hull 31 of a width so as to closely fit movably 30 between the outer flanges of the track on which the ship is arranged, and projecting downwardly from the underside of the hull of each ship may be an apertured lug, as 32. The lug 32 of each of the ships is 35 movably disposed between the inner flanges of its respective track, and to the lug of each ship is attached one end of a line or cable 35. All of the cables 35 are arranged in the grooves, or spaces between the inner 40 flanges of the tracks, and the other ends of the cables are connected to a drum, as 36, which may be provided at one end of the tracks for being manually, or otherwise revolved by means of a handle 37 on one end 45 of the drum so that by rotating this drum the cables will be wrapped thereon for moving the ships forwardly on the tracks.

In order to represent firing of the guns 50 of the ships 27 to produce the effect of a battle between the opposing fleets, projecting from the free ends of the barrel of each of the guns 28 is a lamp 38 all of which are 55 preferably adapted to be electrically lighted, and in the hull of each of these ships is arranged a normally open electric circuit 39 Figs. 2 and 9. Each of the circuits 39 may lead from any suitable source of supply of 60 electricity but each circuit preferably leads from a battery, as 40, carried in the hull of each ship. Each of the circuits 39 is composed of a wire 41 leading from one terminal of the battery 40 to a wire 42 having each of its ends connected to one of the corresponding poles of each of the lamps 38, 65 and from the second terminal of the bat-

tery is a wire 42^a leading to a wire 43 having each of its ends connected to one of the corresponding poles 44 of contacts 45 and 46 provided at spaced intervals on the exterior of the upper part of the hull of each 70 of the ships 27, each of these contacts having a second pole 47 which is slightly spaced from the pole 44 of its contact. To the second pole 47 of the contact 45 is a wire 48 leading to the second pole of one of the 75 lamps 38, and to the pole 47 of the contact 46 is connected a wire 49 leading to the second pole of the other lamp 38. By arranging the circuits 39 in this manner the lamps of each battle ship may be alternately 80 lighted, and to give the effect of the guns being fired the bulbs of each of the lamps may be of a red or other suitable color. To cause the circuit 39 of each of the ships 27 to be alternately closed when the fleets are 85 in action, the contacts 45 and 46 of each circuit are arranged in the path of movement of spaced switches, as 50 and 51, all of which may be similarly formed. Each of the switches 50 and 51 of each circuit has 90 an elongated body 52, and one end of the body of each switch is pivoted, at 53, to the exterior of the hull of the ship so that both switches of each ship may be swung upwardly and downwardly to and from engagement with the contacts 45 and 46 of the electric circuit of the ship. The other end of each of the switches is enlarged to form a head 54, and these heads are of sufficient weight to cause each switch to depend downwardly in spaced relation to the contacts 45 and 46. The switches may be of insulated material, and on the top of the body 52 of each switch is a metal plate 55 of a length to bridge the poles of its contact.

By spacing the contacts 45 and 46 as well as the switches 50 and 51 one in the fore part of each ship and the other in the aft of the ship the lamps of each ship may be alternately lighted when the switches of each ship are swung into engagement with the contacts of the electric circuit of the ship, and to accomplish this, I provide on the tracks of the ships 27 a number of spaced trips, as 56, all being preferably alike in formation, and each of these trips has a plate 57, Fig. 2, with a projecting finger, as 58, formed with a tapered, or beveled free end, as at 59, while through the central part of the plate is a vertically disposed elongated 100 opening 60. A desired number of the trips 56 are arranged at spaced intervals on the outer flange 24 of the tracks of each of the ships 27 so that the plates 57 will lie against the flanges and so that the fingers 58 of the plates will extend above the tracks for the beveled edges 59 of the fingers to be in the path of movement of the swinging switches 50 and 51 of the ships, and to allow the plates and the fingers of the trips to be ad- 105 110 115 120 125 130

justed upwardly and downwardly for being properly contacted by the heads 54 of the switches, through the elongated opening 60 of each plate is passed a set screw, as 61, which is threaded in an opening in the outer flange of its track.

When the drum 36 is revolved to wrap the cables 35 of the ships 27 thereon to move these ships a battle between the ships of the 10 fleets will be represented when the switch 51 of the electric circuit of each ship contacts with one of the trips 56, the trips being adjusted so that the fingers 58 thereof will cause the switches 51 to be swung upwardly 15 to engagement with the contacts 46 of the electric circuits of the ships. The electric circuit of each of the ships 27 will then be closed from the battery 40, over the wire 42 to one pole of the lamp 38 in the fore part 20 of the ship, and from the battery the circuit will pass over the wire 42^a, and over the wire 43, through the switch 51, and over the wire 49 to the second pole of this lamp which in turn will be lighted for an instant as the 25 switch 51 of each ship after passing over each trip will be automatically lowered by reason of the weight of its head 54 for releasing the switch from engagement with the contact 46 to extinguish the light of these 30 lamps. When the ships 27 are moved farther along the tracks the switches 50 of the electric circuits of the ships will likewise contact with the trips, to cause the switch 50 of each ship to be swung into engagement with 35 the contact 45 of the electric circuit of the ship. The circuit will thereby be closed from the battery 40, over the wire 42 to one pole of the lamp 38 in the aft of the ship, and from the battery the current will flow 40 over the wire 42^a, over the wire 43, through the switch 52, and over the wire 48 to the second pole of this second lamp. The lamps in the aft of the ships 27 will thereby be lighted also for an instant to represent firing of the 45 guns, as these lamps will be extinguished in the manner above explained when the switches 50 are freed from engagement with the trips.

To cause one or more of the lamps of the 50 ships 27 to be lighted and extinguished in quick succession for representing an active bombardment at intervals during the progress of the battle, on the track of each of these ships may be arranged a series of movable trips, as 62. Each of the trips 62 consists of a belt 63 of a suitable length, and each belt is guided over a pair of pulleys 64 and 65 revolubly arranged on the flange 24 of the track of each of the ships, the pulleys 60 of each pair being spaced so that the belt thereon will be held quite taut. Projecting from the belt 63 of each of the movable trips 62 are a number of spaced fingers 66, and these fingers of each belt are disposed in the 65 path of movement of the switches 50 and 51

of the electric circuit 39 of each of the ships 27. When the battle ships 27 are moved on the tracks provided with these movable trips the switches 51 and 50 of the electric circuit of each ship will consecutively contact with 70 the fingers 66 for operating the switches to close the circuit in a way similar to closing the circuits of the ships by the trips 56, as hereinbefore explained, and when it is desired to light the lamps in quick succession 75 to represent a very active bombardment the belts 63 with the fingers 66 of one or all of the movable trips may be rapidly moved on the pulleys 64 and 65 by manually turning a crank handle 67 provided on the shaft 68 of 80 a pulley 64 of each of these trips.

The battle ships 29 are provided for representing one or more of the ships of each fleet as set on fire during the bombardment by the other ships 27, and part of the hull 85 of each of the ships 29 at the magazine 30 may be cut-out to provide an opening which is closed by a red or other colored plate of glass, as 69, so that when the combustible material, as 70, is ignited the flame will appear in color accordingly. Arranged in the magazine 30 of each of the ships 29 is a spark plug 71, and the spark plug of each of the ships is energized through the medium of a normally open electric circuit 72, 90 Figs. 6 and 10, provided in each ship. Each of the circuits 72 may lead from any source of electricity supply, preferably from a battery, as 73, arranged in each of the ships 29, and from one terminal of each of these batteries is a wire 74 leading to one pole of the spark plug of its respective circuit. From the second terminal of the battery in each ship is a wire 75 leading to one pole 76 of a contact 77 having a second pole 78 which is 95 spaced from the pole 76, this contact of the circuit of each ship being provided exteriorly of the hull of the ship. From the pole 78 of the contact 77 of each circuit is 100 a wire 79 leading to the second pole of the 105 spark plug of the circuit of each ship, and to produce sufficient resistance in each of these circuits to energize the spark plugs 71 for igniting the combustible material in the magazines in each circuit is provided an 110 induction coil, as 80, the ends of the wires of which are connected to the wires 75 and 79. To permit the circuit 72 of each of the ships 29 to be alternately closed and opened 115 for energizing the spark plug 71 thereof, on the exterior of the hull of each of these ships is a switch, as 81. The switches 81 are similarly formed to the switches 50 and 51 of the electric circuits of the ships 27 as well as being arranged on the ships 29 so 120 as to be operated for closing the circuits 72 in a manner similar to the operation of the switches 50 and 51 of the electric circuits 39, for instance when the switch 81 of each 125 of the ships 29 is swung upwardly its plate 130

55 will engage the poles of the contact 77, and the electric circuit 72 of the ship will be closed from the battery 73, over the wire 74 to one pole of the spark plug 71, and the current will be delivered over the wire 75 to the contact 77, through the switch 81, and over the wire 79 to the second pole of the plug which in turn will be energized to produce a spark for igniting the combustible material in the magazine 30 of each of the ships 29. One or more of the ships 29 of each fleet may thereby be represented as being set on fire during the battle between the fleets, and the switches 81 of the electric circuits 72 are operated at intervals to close the circuit of each ship by providing one or more spaced trips on the track 82 each being of a similar formation to the trips 56 as well as co-acting with the switches 81 in the same manner as above explained.

For the purpose of representing objects on land as being bombarded by one or both fleets as well as being destroyed, on the land portion 11 of the support 10 may be provided a number of objects in the forms of buildings, as 83 and 84. These buildings may be of any desired types, and in parts of each building may be provided openings covered with red, or other colored plates of glass, as 85, while the windows and doors of the buildings may be likewise covered with colored glass. Interiorly of each of the buildings may be a suitable number of lamps 86 of forms adapted to be lighted by electric circuits 87 and 88. Each of the electric circuits 87 and 88 may lead from one of the tracks on which one of the ships 27 is movable, and in order to represent the destruction of one, or more of the buildings at periods immediately subsequent to the "firing" of the ships on the respective tracks, included in each of the circuits may be one of the trips 56 for first operating the switches 50 and 51 to close the circuit 39 of each ship whereby the lamps thereof may be lighted to cause a representation of the bombardment of the land objects. The circuit 87 may lead from any suitable source of supply of electricity, such as a battery 89, and from one terminal of this battery is a wire 90 leading to the trip 56 toward which the ship is moving. Connected to the trip 56 is a wire 91 leading to one of the poles of the lamp in one of the buildings, and from the second pole of this lamp is a wire 92 leading to one of the poles of the lamp in the second building, as shown in Fig. 1.

When a number of lamps are used in one or more of the buildings so as to be lighted simultaneously the lamps may be wired in series in any suitable manner, for example, as shown in Fig. 7, the second series may be connected by a wire, as 92^a, while from one of the poles of one of the second series may be a wire 92^b leading to the wire 91. From

the second terminal of the battery 89 is a wire 93 leading to a contact 94 to which is connected a switch, or bridge, as 95, Fig. 2, which is fixed on the track of the moving ship 27 contiguous to the trip 56, and this switch is also connected to a contact 96 from which leads a wire 97 to the second pole of one of the lamps connected by the wire 92. Leading from the wire 93 is a wire 98 having its other end connected to a switch 99 adapted to be manually swung into and out of engagement with a contact 100. This switch is arranged on the track of the moving ship for allowing the circuit 87 to be opened and closed at suitable intervals to cut-in and cut-out this circuit, and from the contact 100 is a wire 101 leading to the second pole of one of the lamps connected by the wire 92^a. The circuit 88 leads from one of the tracks of the second fleet of ships to the circuit 87 by two wires 102 and 103 one being connected to the wire 91 of the circuit 87, while the wire 103 leads to the wire 101 also of the circuit 87. The current passing over these wires are supplied from a second battery 104, from the terminals of which are wires arranged similar to the wires of the circuit 87, and in which are provided one of the trips 56, a fixed switch 105 and a manually operative switch 106, Fig. 1, these switches corresponding respectively to the switches 95 and 99 of the circuit 87 so as to be likewise operated for lighting the lamps in the land objects by one of the ships of the second fleet when desired. Both of the electric circuits are adapted to be closed independent of each other, and to close the circuits by the ships when moving on the tracks thereof on the underside of the hull of each ship is a metal shoe 107, and these shoes are arranged to contact with the switches 95 and 105 when the ships are moved accordingly on the tracks. For instance, when one of the ships 27 is moved on its track, and when it is desired to represent the bombardment of the land objects by lighting the lamps 86 with the electric circuit 87 this circuit is closed by swinging the switch 99 into engagement with the contact 100 of the switch. When the ship is moved to this electric circuit one of the lamps 86 will be lighted to represent the bombardment of the land objects by the circuit 39 of the ship being closed by successive co-action between the switches 51 and 50 and the trip 56 of this circuit, as hereinbefore explained, and when the ship is moved so that its shoe 107 subsequently contacts with the stationary switch 95 of the circuit, the circuit will be closed from one terminal of the battery 89, over the wire 90, through the trip 56, over the wire 91, to the lamps, and the second terminal of the battery of the circuit will be closed over the wire 93, through the switch 95, over the wire 97; also over the wire 98, 130

- through the switch 99, over the wire 101, and through wires 92^a, 92^b and 90 to and through the lamps, the circuit 88 being closed in a similar manner from its battery 5 104 to the lamps in the land objects when one of the ships 27 of the second fleet is moved on its track to likewise close this circuit over its respective wires after the switch 106 of the circuit is closed.
- 10 In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.
- 20 Having thus described my invention, I claim as new and desire to secure by Letters Patent:—
1. In a mechanical battle, a plurality of tracks, a war ship member movable on each track and having guns, a lamp on each of the guns, a normally open electric circuit on each ship member leading to each lamp for lighting the lamps, operative means on each ship member whereby the electric circuit may be closed and opened, and a trip on each track, adapted when the ship members are moved to coact with the operative means of each ship member to close the circuit thereof so that the lamps may be 25 lighted.
  2. In a mechanical battle, a plurality of tracks, a war ship member movable on each track and having guns, a lamp on each of the guns, a normally open electric circuit on each ship member leading to each lamp for lighting the lamps, a switch on each ship member whereby the electric circuit may be closed and opened, and a trip on each track, adapted when the ship members are moved 30 to coact with the switch of each ship member to close the circuit thereof so that the lamps may be lighted.
  3. In a mechanical battle, a plurality of tracks, a war ship member movable on each track and having guns, a lamp on each of the guns, a normally open electric circuit on each ship member leading to each lamp for lighting the lamps, a plurality of switches on each ship member whereby the electric circuit may be closed and opened to alternately light the lamps, and a plurality of spaced trips on each track, adapted when the ship members are moved to coact 35 with each switch of each ship member to close the circuit thereof so that the lamps may be successively lighted.
  4. In a mechanical battle, a plurality of tracks, a war ship member movable on each track and having guns, a lamp on each of the guns, a normally open electric circuit on 40
- each ship member leading to each lamp for lighting the lamps, and means adapted when each ship is moved to cause the circuit to be opened and closed whereby the lamps of each ship will be successively lighted. 70
5. In a mechanical battle, a plurality of tracks, a war ship member movable on each track and having guns, a lamp on each of the guns, a normally open electric circuit on each ship member leading to each lamp 75 for lighting the lamps, operative means on each ship member whereby the electric circuit may be closed and opened, a plurality of spaced stationary trips on each track, adapted when the ship members are moved to coact with the operative means of each ship member to close the circuit thereof at intervals so that the lamps may be successively lighted, and a movable series of trips on each track to operate the operative means for 80 closing the circuit of each ship to cause the lamps to be lighted in quick succession independent of the lighting of the lamps by the stationary trips.
6. In a mechanical battle, a plurality of 85 tracks, a war ship member movable on each track and having guns, a lamp on each of the guns, a normally open electric circuit on each ship member leading to each lamp for lighting the lamps, a switch on each ship member whereby the electric circuit may be closed and opened, a plurality of spaced stationary trips on each track, adapted 90 when the ship members are moved to coact with the switch of each ship member to 95 close the circuit thereof at intervals so that the lamps may be successively lighted, and a movable series of trips on each track to operate the switch of each ship member for closing the circuit of the ship to cause the lamps to be lighted in quick succession independent of the lighting of the lamps by the stationary trips. 100
7. In a mechanical battle, a plurality of 105 tracks, a war ship member movable on each track and having guns, a lamp on each of the guns, a normally open electric circuit on each ship member leading to each lamp for lighting the lamps, a plurality of switches on each ship member whereby the electric circuit may be closed and opened to alternately light the lamps, a plurality of spaced stationary trips on each track, adapted when the ship members are moved to coact 110 with each switch of each ship member to close the circuit thereof so that the lamps may be successively lighted, and a movable series of trips on each track to operate the switches of each ship member for closing the circuit of the ship to cause the lamps to be lighted in quick succession independent of the lighting of the lamps by the stationary trips. 115
8. In a mechanical battle, a plurality of 120 tracks, a war ship member movable on each track and having guns, a lamp on each of the guns, a normally open electric circuit on 125

track, each with a magazine for combustible material, a spark plug in each magazine in contact with the combustible material, a normally open electric circuit on each ship member whereby the spark plug of each ship may be separately energized, operative means on each ship whereby the electric circuit may be opened and closed, and a trip on each track, adapted when the ship members are moved to coact with the operative means of each ship member to close the circuit thereof so that spark plugs may be separately energized at intervals.

9. In a mechanical battle, a plurality of tracks, a war ship member movable on each track, each with a magazine for combustible material, a spark plug in each magazine in contact with the combustible material, a normally open electric circuit on each ship member whereby the spark plug of each ship may be separately energized, a switch on each ship whereby the electric circuit may be opened and closed, and a trip on each track, adapted when the ship members are moved to coact with the switch of each ship member to close the circuit thereof so that the spark plugs may be separately energized at intervals.

10. In a mechanical battle, a plurality of tracks, a war ship member movable on each track each with a magazine for combustible material, a spark plug in each magazine in contact with the combustible material, a normally open electric circuit on each ship member whereby the spark plug of each ship may be separately energized, and means whereby the electric circuit may be closed to separately energize the spark plugs at intervals.

11. In a mechanical battle, a plurality of tracks, a war ship member movable on each track, a number of the ship members being provided with guns while each of the others is provided with a magazine for combustible material, a lamp on each of the guns, a spark plug in each magazine in contact with the combustible material, a normally open electric circuit on each ship member whereby the lamps may be alternately lighted and the spark plug of each ship may be separately energized, operative means on each ship whereby the electric circuit may be opened and closed, and a trip on each track, adapted when the ship members are moved to coact with the operative means of each ship member to close the circuit thereof so that the lamps may be lighted and so that the spark plugs may be energized at intervals.

12. In a mechanical battle, a plurality of tracks, a war ship member movable on each track, a number of the ship members being provided with guns while each of the others is provided with a magazine for combustible material, a lamp on each of the guns, a

spark plug in each magazine in contact with the combustible material, a normally open electric circuit on each ship member whereby the lamps may be alternately lighted and the spark plug of each ship may be separately energized, a switch on each ship whereby the electric circuit may be opened and closed, and a trip on each track, adapted when the ship members are moved to coact with the switch of each ship member to close the circuit thereof so that the lamps may be lighted and so that the spark plugs may be energized at intervals.

13. In a mechanical battle, a plurality of tracks, a war ship member movable on each track, a number of the ship members being provided with guns while each of the others is provided with a magazine for combustible material, a lamp on each of the guns, a spark plug in each magazine in contact with the combustible material, a normally open electric circuit on each ship member whereby the lamps may be alternately lighted and the spark plug of each ship may be separately energized, means on each ship whereby the electric circuit may be closed so that the lamps may be lighted and so that the spark plugs may be energized at intervals.

14. In a mechanical battle, a plurality of tracks, a war ship member movable on each track and having guns, a lamp on each of the guns, a normally open electric circuit on each ship member leading to each lamp for lighting the lamps, operative means on each ship member whereby the electric circuit may be closed and opened, a trip on each track, adapted when the ship members are moved to coact with the operative means of each ship member to close the circuit thereof so that the lamps may be lighted, a land object with lamps therein, an electric circuit leading from the track of one of the ship members to the lamps of the objects, and means whereby the latter circuit may be closed to light the lamps in the land objects following the lighting of the lamps in the ship.

15. In a mechanical battle, a plurality of tracks, a war ship member movable on each track and having guns, a lamp on each of the guns, a normally open electric circuit on each ship member leading to each lamp for lighting the lamps, a switch on each ship member whereby the electric circuit may be closed and opened, a trip on each track, adapted when the ship members are moved to coact with the switch of each ship member to close the circuit thereof so that the lamps may be lighted, a land object with lamps therein, an electric circuit leading from the track of one of the ship members to the lamps of the objects, and means whereby the latter circuit may be closed to light the lamps in the land objects following the lighting of the lamps in the ship.

16. In a mechanical battle, a plurality of tracks, a war ship member movable on each track and having guns, a lamp on each of the guns, a normally open electric circuit on each ship member leading to each lamp for lighting the lamps, operative means on each ship member whereby the electric circuit may be closed and opened, a plurality of spaced stationary trips on each track, adapted when the ship members are moved to coact with the operative means of each ship member to close the circuit thereof at intervals so that the lamps may be successively lighted, a movable series of trips on each track to operate the operative means for closing the circuit of each ship to cause the lamps to be lighted in quick succession independent of the lighting of the lamps by the stationary trips, a land object with lamps therein, an electric circuit leading from the track of one of the ship members to the lamps of the objects, and means whereby the latter circuit may be closed to light the lamps in the land objects following the lighting of the lamps in the ship.

17. In a mechanical battle, a plurality of tracks, a war ship member movable on each track, a number of the ship members being provided with guns while each of the others is provided with a magazine for combustible material, a lamp on each of the guns, a spark plug in each magazine in contact with the combustible material, a normally open electric circuit on each ship member whereby the lamps may be alternately lighted and the spark plug of each ship may be separately energized, operative means on each ship whereby the electric circuit may be opened and closed, a plurality of spaced stationary trips on each track, adapted when the ship members are moved to coact with the operative means of each ship member to close the circuit thereof at intervals so that the lamps may be successively lighted and so that the spark plugs may be energized at intervals, a movable series of trips on each track to operate the operative means for closing the circuit of each ship with lamps to cause the lamps to be lighted in quick succession independent of the lighting of the lamps by the stationary trips, a land object with lamps therein, an electric circuit leading to the lamps of the object from the track of one of the ships with lamps, and means whereby the latter circuit may be closed to light the lamps in the land object following the lighting of the lamps in the ship.
